UNITED STATES PATENT OFFICE.

HARRY P. SARCHETT, OF NOWATA, OKLAHOMA.

SASH-HANGER.

971,313.

Specification of Letters Patent. Patented Sept. 27, 1910.

Application filed April 5, 1910. Serial No. 553,638.

To all whom it may concern:

Be it known that I, HARRY P. SARCHETT, a citizen of the United States, and a resident of Nowata, in the county of Nowata and State of Oklahoma, have invented a new and Improved Sash-Hanger, of which the following is a full, clear, and exact description.

This invention relates to sash hangers for movably supporting storm sashes, screen frames and the like, and has reference more particularly to a device of this class comprising hanger brackets adapted to be secured to a screen frame, and having pivots, and socket members adapted to be secured to a window frame and having slots extended intermediate their ends, to edges of the members, to permit the introduction of the pivots into the slots.

The object of the invention is to provide simple, strong and durable hangers, by means of which storm sashes, screen frames, and similar devices can be mounted in position in window frames, which can be manufactured inexpensively, which can be applied to the window frame from the inside of the building, which are adapted to be protected from the weather by the window frame itself, thereby obviating rust streaks, or other disfigurements of the building, and by means of which the frames can be pivotally and removably mounted in place.

The invention consists in the construction and combination of parts to be more fully described hereinafter and particularly set forth in the claims.

Reference is to be had to the accompanying drawings, forming a part of this specification, in which similar characters of reference indicate corresponding parts in all the views, and in which—

Figure 1 is a front elevation of the upper part of a window frame showing a screen frame mounted in place therein, by means of my invention, parts of the window frame and the screen frame being broken away; Fig. 2 is an enlarged vertical section of the upper part of a window frame, showing a screen frame mounted in position by means of my hangers; Fig. 3 is a perspective view of the socket member of a hanger; Fig. 4 is a perspective view of a hanger bracket; and Fig. 5 is an enlarged transverse section on the line 5—5 of Fig. 2.

Before proceeding to a more detailed explanation of my invention, it should be clearly understood that the hangers can be

used for mounting in position in window frames and other structural openings, screen frames, storm sashes, or other like devices, which it is desired to support pivotally and removably at the openings. The parts of the hangers are preferably fashioned from sheet metal or similar material, by stamping and bending.

Certain of the details of construction form no part of the invention, and can be altered in accordance with individual preference and special conditions, without departing from the underlying spirit of the invention.

Referring more particularly to the drawings, I have shown for example, a window frame 10, having the usual blind stop 11, against which the screen frame 12 rests. I employ socket members 13, consisting of a body plate 14, having at one end a laterally disposed flange 15, and at the other end an offset flange 16, the flanges having openings 17 and 18 respectively, intended for the reception of retaining screws by means of which the socket member is mounted in position. At the inner edge, the body plate has a laterally disposed flange 19, the width of which corresponds to the degree of offsetting of the flange 16. The body plate has formed therein a slot 20, the rear edge of which is rounded, and which has a lower, rounded bearing end 21, and an upper rounded end 22. The slot has an extension 23 to the forward edge of the body plate, that is, to the edge opposite the flange 19, for a purpose which will appear hereinafter.

I employ hanger brackets 24 consisting of a main plate 25 provided with screw holes 26. The plate has a laterally disposed flange or arm 27, provided, near the end, with an opening 28, in which is arranged the extremity of a pivot or trunnion 29. The latter has the extremity 30 riveted in the opening 28, so that it is securely mounted in place. At the free end, it has a laterally extended head 31.

The pivots 29 of the hanger brackets are received in the slots 20 of the socket members, to mount the screen plates pivotally in place. The pivots are introduced into the slots through the extensions 23 of the same. When the pivots rest at the lower bearing ends 21 of the slots, the screen frame can be swung outwardly and inwardly, pivotally, as is indicated in Fig. 2. When the screen is swung inward against the blind stop 11, the lower edge of the screen rides

upon the lower part of the window frame, so that the upper portion of the screen frame is raised, and the pivots are caused to ride upward in the slots into the upper extremities 22 thereof, where they are securely retained in place, and prevent the opening of the screen frame.

The socket members and the hanger brackets are securely mounted in position by means of suitable screws 32 or the like. The hanger brackets are mounted in place at the upper corners of the screen frame, with the arm 27 projecting inwardly with respect to the window. The socket members are located in the upper corners of the window frame, at the blind stop, the flanges 15 being located against the horizontal upper member, and the flanges 16 against the side members. In this way the socket members are located within the window frame, and are, to a large extent, protected from the influence of the weather.

Having thus described my invention, I claim as new, and desire to secure by Letters Patent:

1. The combination with a window frame, and a screen frame, of socket members secured in the corners of the window frame and each formed of a plate offset adjacent to one end to form a flange and provided at its other end with a lateral flange, said flanges being apertured, the plate being provided with an inclined slot having rounded ends and an extension leading out through one side of the plate, and hanger brackets secured to the screen frame and each formed of a plate having a lateral flange at one side and provided with a headed pivot projecting at right angles from the flange, said pivots engaging the slots of the socket members.

2. In a device of the class described, a socket member adapted to be secured to a

window frame and formed of a plate offset adjacent to one end to form a flange and provided at its other end and at one side with lateral flanges, the side flange being of a width equal to the offset of the plate and the flanges at the ends of the plate being apertured, the said plate being provided with an inclined slot having rounded ends and an extension leading out through the side of the plate opposite that having the flange, and hanger brackets adapted to be secured to a screen frame and each formed of an apertured plate having a lateral flange projecting from one side and provided with a headed pivot projecting at right angles from the flange, and adapted to enter the slot of the bracket member.

3. In a device of the class described, a socket member adapted to be secured to a window frame and formed of a plate offset adjacent to one end to form a flange extending parallel with the plate and provided at its other end with a lateral right angular flange projecting in a direction opposite to the said offset, said flanges being apertured, the plate being provided with an inclined slot having rounded ends and an extension leading out through one side edge of the plate, and a hanger bracket adapted to be secured to a screen frame and formed of an apertured plate having a lateral flange at one side and provided with a headed pivot projecting at right angles from said flange and adapted to enter the slot of the socket member.

In testimony whereof I have signed my name to this specification in the presence of two subscribing witnesses.

HARRY P. SARCHETT.
